Inventor:

George Schubert.

UNITED STATES PATENT OFFICE.

GEORGE SCHUBERT, OF WALNUT SPRINGS, TEXAS.

BALING-PRESS.

SPECIFICATION forming part of Letters Patent No. 517,936, dated April 10, 1894.

Application filed February 20, 1893. Serial No. 462,948. (No model.)

To all whom it may concern:

Be it known that I, GEORGE SCHUBERT, a citizen of the United States, residing at Walnut Springs, in the county of Bosque and 5 State of Texas, have invented certain new and useful Improvements in Baling-Presses; and I do hereby declare the following to be a full, clear, and exact description of the invention, such as will enable others skilled in the art to 10 which it appertains to make and use the same, reference being had to the accompanying drawings, forming part of this specification, in which drawings—

Figure 1 is a plan view of a baling press 15 provided with my improvements, and Fig. 2, is a front end view of same.

This invention relates to baling presses provided with runners, (instead of the usual wheels,) to be moved about the field; and my 20 objects are, to construct such a press in such a manner that it can be readily started down with but few stakes, second; to provide a rigid but removable side brace to prevent the press from canting, and third; to prevent 25 the operating lever from canting or swinging upward or downward when in operation; and to promote simplicity.

Referring to the drawings; A, represents the frame bars of the press, retained in position 30 by the cross frames C, C, said bars A, extend forward a proper distance, to receive the bolster plates e to receive the king bolt a, on which is pivoted the operating lever D. The king bolt a is extended above the frame 35 bars A, a proper distance to receive the brace D', which is rigidly framed in the lever D by the stay bar D².

f is a pin in the upper end of the king bolt, to retain the king bolt in position. 40 The upper end of the brace D' is provided with a strip g by which it is pivoted on the king bolt a.

B, B are runners secured to the cross bar C', and to the lever end of the cross frames C, C, 45 and to the lower end of the posts J and J'. Said posts J and J' are also secured to the end

of the frame bars A, the post J' projects upward beyond the frame bars A, and with its upper end slotted to receive the brace j.

i designates a stirrup extending over the 50 brace j, and secured to the post J'. i' is a similar stirrup extending over said brace with ample space above the brace j to admit the wedge j' to rigidly secure the brace in position, said stirrup i' is secured to the upper 55 end of post J, as shown.

t designates a strip on the lower end of the brace j, to receive a stake.

h designates a strip forming a clevis and secured to the lower end of the post J' and 60 bar B in position to receive a stake. h' is a similar clevis on the cross bar C', to hold the press in position.

n, n, are angle irons secured to the cross 65 bar C' and to the lower frame bars A.

s designates the bottom board of the press and u the upper board and v designates the feeding chamber.

P are tension rods passing through the cross bars o, o.

L, L, designate set blocks and k are tripping blocks employed to operate on the plunger bar, not shown in the drawings.

Having thus described my invention, what I claim is—

In a baling press, having runners B, B, frame bars A extending beyond the feeding chamber, posts J and J' secured to the frame bars A, a cross bar C', a clevis h' on said cross bar C', a clevis h, a brace j extending over the 80 post J, and in the slot of the post J', stirrups i and i' secured to the upper end of the posts J and J' extending over the brace j, a wedge j' on the brace j and in the stirrup i', as and for the purpose described.

In testimony whereof I have affixed my signature in presence of two witnesses.

GEORGE SCHUBERT.
